CARRIAGE RETURN MECHANISM FOR
RECORD MAKING MACHINESOscar W. Swanson, West Hartford, Conn., as-
signor to Underwood Corporation, New York,
N. Y., a corporation of Delaware

Application November 19, 1947, Serial No. 786,826

17 Claims. (Cl. 197—66)

1

This invention relates to record printing machines of the class having a carriage which is movable in one direction to shift the position of the printing mechanism transversely of a work sheet and in the opposite direction to return the printing mechanism to position for starting another line.

The invention relates more particularly to power operated carriage return mechanism for such machines.

The principal objects of the present invention are to improve the construction and mode of operation of power operated carriage return mechanisms for machines of the above class and to produce a novel mechanism which will operate in a reliable manner to return the carriage alternatively to any one of two or more returned positions.

Other objects of the invention are to provide a carriage return mechanism for record printing machines, having a projectible stop for engagement with a co-operating arrester to arrest the return movement of the carriage, with novel and improved mechanism for projecting said stop, with novel and improved mechanism for holding the stop in projected position and with novel and improved mechanism for releasing the stop to enable the same to be retracted to normal position.

Another object of the invention is to provide an improved power operated carriage return mechanism constructed to enable the carriage to be returned to full return position or to one or more partial return positions and particularly adapted for use on typewriting machines of the so-called Elliott Fisher type in which the work is supported on a flat platen and the type mechanisms are mounted on a carriage which is movable transversely across the machine and over the platen in one direction to letter space and in the opposite direction to return the same to position to start the next line of writing.

A still further object of the invention is to produce a carriage return mechanism for typewriting machines of the Elliott Fisher type having a control mechanism by which the driving and stopping of the carriage may be more easily and conveniently controlled than in prior carriage return mechanism for machines of this particular type.

With the above and other objects in view, the invention consists in a machine embodying the novel and improved features, constructions and combinations of parts hereinafter described and particularly pointed out in the claims, the

2

advantages of which will be readily understood by those skilled in the art.

The invention will be clearly understood from the accompanying drawings illustrating the invention in its preferred form and the following detailed description of the construction therein shown.

In the drawings,

Fig. 1 is a perspective view illustrating certain parts of a typewriting machine of the Elliott Fisher type embodying the invention.

Fig. 2 is a view in side elevation partly in section illustrating the type carriage, the carriage return mechanism and certain devices for controlling said mechanism and the stopping of the return movement of the carriage,

Fig. 3 is a view similar to Fig. 2 illustrating certain of the parts in different positions,

Fig. 4 is a detail view in side elevation illustrating a portion of the mechanism shown in Fig. 3, with certain of the parts removed to show more clearly the structure, and

Fig. 5 is a detail view in side elevation illustrating one of the carriage return keys and the associated key bar detached from the machine.

The invention is illustrated in this application as embodied in a machine having the same general construction arrangement and mode of operation of parts as the machine disclosed in the patent to Foothorap No. 1,904,127, dated April 18, 1933.

The machine illustrated in this application is provided with a flat platen 2 mounted in a rectangular platen frame comprising a pair of parallel side bars 4 suitably supported on a standard, not shown. A portion of each bar is toothed to form a rack 5 engageable by traction gears 6 fast on a shaft 8 extending transversely of the side bars and supported by bearings in brackets, one of which is shown at 10 projecting upwardly from the rear portions of the side members of the rectangular line space frame 12. This shaft also carries wheels 14 engaging tracks 16 formed on the side bars 4 and the front rail 18 of the line space frame is likewise supported by wheels (not shown) engaging said tracks to enable the line space frame to move forwardly and rearwardly along said tracks.

The front and rear cross rails 18 and 20 support a key carriage 22, shown in dot-and-dash lines in Fig. 1 for travel across the platen 2 in letter spacing direction and return, on front and rear wheels 24.

The key carriage contains the customary key actions, ribbon mechanism and controls for the

carriage escapement which it is not considered necessary to illustrate in this application. The carriage escapement, which preferably is employed on the present machine, is similar to that shown and described in the patent to Foothrap No. 1,203,519, dated October 31, 1916, and in the patent to Sundstrand No. 2,370,505, dated February 27, 1945. The usual spring barrel 26 is mounted on the line space frame 12, a tape 28 connecting the spring barrel 26 with the key carriage 22 to draw the carriage toward the right in letter spacing direction under control of the escapement mechanism.

Power drive

The key carriage 22 may be manually returned to the left-hand margin from any point to which it has been advanced in letter spacing direction, but to relieve the operator of the work of returning the carriage, a motor 30 is provided, conveniently mounted on a casting (not shown) secured to and projecting rearwardly from the rear rail 20 of the line space frame 12 with which it travels.

Referring to Fig. 2 of the drawings, power from the motor is taken from the worm 32 fast on the motor shaft 34 and meshing with a worm gear 36 having a friction clutch connection 38 with a countershaft 40 journaled in the casting and extending forwardly beneath a carriage return rack 42 secured to the flanged rear end of an apron 44 projecting from the deck 46 of the key carriage 22.

A wide carriage return pinion 48, journaled on the forward end of the countershaft 40 and axially movable along the shaft, meshes with the teeth of the carriage return rack 42 at all times, the return pinion having a peripherally grooved collar 50 terminating at its rear end in a driven clutch member 52 normally disengaged from a driving clutch member 54 fast on the countershaft.

The free end of a clutch shift finger 56 lies in the groove in the sliding rotatable collar 50, the finger being secured to a clutch shifting shaft 58 journaled in the motor support casting. A clutch shifting arm 60 on one end of the clutch shifting shaft 58 is provided with a lateral locking lip 62 normally engaged by a locking latch 64 pivoted on a trip shaft 66 extending across the machine and supported in bearings projecting from the back of the rear rail 20 of the line space frame. A fan-shaped trip arm 68 secured to the trip shaft 66 extends rearwardly between two studs 70 and 72 projecting respectively from the hooked latch 64 and from the clutch shifting arm 60, a normally tensioned spring 74 connecting the two studs to form a yielding link therebetween and normally maintaining the hooked latch 64 engaged with the clutch shifting arm 60 to retain the clutch members 52 and 54 disengaged.

Control of automatic carriage return mechanism

Curved arms 76 projecting upwardly and forwardly from the trip shaft 66 support a tripping bail 78 toothed at its opposite ends and rocking with the shaft 66. Mounted on the right-hand end of the tripping bail is a cam block 80 (see Fig. 1) arranged to be engaged by a roll 82 projecting downwardly from the carriage apron.

In the normal position of the parts, the hooked latch 64 is engaged over the lip 62 of the clutch shifting arm 60, as shown in Fig. 2, the trip shaft 66 is retained in its limiting counterclock-

wise position, and the tripping bail 78 is retained in its rearmost position by the action of the spring 74. As the carriage 22, traveling in letter spacing direction, advances the printing point toward the extreme right-hand margin of the work sheet, the roll 82 wipes across the inclined face of the cam block 80 and rocks the bail forwardly thereby rocking the trip shaft 66 in a clockwise direction, Fig. 2.

10 The rearwardly projecting trip arm 68 is swung upwardly by the rocking movement of the trip shaft 66 to disengage the hooked latch 64 from the clutch shifting arm 60 and, in so doing, additionally tensions the spring 74, which spring, acting as a tension link, swings the arm 60 and rocks the clutch shifting shaft 58 and its clutch shifting finger 56 counterclockwise, Fig. 2, to slide the driven member 52 of the carriage return clutch along the counter shaft 40 into engagement with the driving member 54, the carriage return pinion 48 being of sufficient width to maintain its engagement with the carriage return rack throughout the clutch shifting action.

15 The motor 30 is preferably of the constantly running type and will then drive the carriage in contra-letter spacing direction toward the left-hand side of the machine. As the carriage approaches the end of its return movement under the influence of the motor 30, the tripping bail 78 is swung back rearwardly to its normal position. During this operation, the tripping arm 68 is pressed against the stud 72 on the clutch shifting arm 60 and rocks said arm together with the clutch shifting shaft 58 and clutch finger 56 in a clockwise direction, Fig. 2, to cause the finger to disengage the driven clutch member 52 from the driving clutch member 54, thereby disconnecting the motor 30 from the traveling carriage 22.

20 The spring 74 tends to draw the hooked latch 64 downwardly, as the tripping arm 68 is swung downwardly and, when the arm 60 reaches a certain position, the latch snaps down over the lip 62 on said arm to lock the clutch shift mechanism, and hence the clutch members, in disengaged positions.

25 All of the mechanisms above described have substantially the same construction, arrangement and mode of operation as the corresponding mechanisms of the machine illustrated and described in the patent to Oscar J. Sundstrand, No. 2,301,716, dated November 12, 1942.

30 The mechanism for swinging the tripping bail 78 rearwardly as the carriage approaches the end of its return movement will be hereinafter described.

Partial carriage return

35 The present machine is provided not only with mechanism for automatically returning the carriage to position to begin the typing of a line, but is also provided with mechanism for stopping the carriage in fully returned position or in either of two partial return positions at different distances to the right of its fully returned position. In carrying out the invention, three carriage return keys are mounted on the key carriage. By the respective actuation of these keys the carriage return mechanism will be thrown into operation and the return movement of the carriage will be caused to be arrested with the carriage in any one of three different return positions, the stop position being selected by the actuation of the appropriate key.

40 The keys controlling the return under power 75 of the carriage from any advanced position to a

selected precedent position are mounted on the traveling carriage 22 and are arranged in a novel manner to enable the selection of any of several precedent positions to which the carriage may be returned. These three keys are indicated respectively at 84, 86 and 88 and are mounted respectively on vertically slidable key bars 90, 92 and 94. These keys are arranged to be independently depressed. The depression of each key, through intermediate mechanism, swings forwardly the tripping bail 78 to engage the driven member 52 of the carriage return clutch with the driving member 54 of said clutch.

The mechanism for actuating the tripping bail to engage the carriage return clutch from the depression of any one of the keys comprises an arm 96 fixed to a horizontal rock shaft 98 journaled in bearings on the key carriage frame, said arm depending through a slot in the apron 44 to a point in proximity to and behind the tripping bail 78. The shaft 98 extends part way across the rear of the key carriage toward the left-hand side thereof and, at its left-hand end, carries a radial arm 100 secured to the shaft. Upon this arm is mounted a pin 102 arranged to be engaged by the cam faces of the teeth 104 of a toothed cam wheel 106 journaled on a pin or stud 108 supported at its inner end on a plate 110 secured to the side plate 111 of the key carriage. By the rotation of the cam wheel 106 in a clockwise direction, Fig. 2, the pin 102 is engaged by one of the teeth of the cam wheel and the arm 100, the rock shaft 98 and the arm 96 are swung in a counterclockwise direction to swing forwardly the trip bail 78 to engage the carriage return clutch.

A one-tooth rotation is imparted to the cam wheel 106 by the depression of any one of the three carriage return keys. The mechanism for imparting this rotation to the cam wheel comprises a longitudinally movable bar or slide 112, the rear end of which is supported on a headed pin 114 fixed to the supporting plate 110 and engaging in a slot 116 formed in the rear portion of the bar. The forward end of the bar 112 is supported upon one arm of a bell crank 118 pivoted at 120 upon a screw stud also fixed in the supporting plate 110. Upon the rear end portion of the bar 112 is pivoted at 122 a pawl 124 having an arm 126 formed with a downwardly extending tooth and arranged to engage the teeth of the cam wheel 106. Pawl 124 is acted upon by a coil spring 128 which tensions the pawl in a direction to maintain the arm 126 constantly in engagement with the teeth of the cam wheel.

The bar 112 is acted upon by coil spring 130 which tends to move the same rearwardly. The movement of the bar rearwardly under the influence of the spring 130 is limited by the engagement of the pin 114 with the forward end of the slot 116. Thus the spring 130 maintains the bar normally in the position shown in Fig. 2, the arm 126 of the pawl 124 then resting upon the outer end of one of the teeth of the cam wheel 106. The bar 112 is moved forwardly to the position shown in Fig. 3 by swinging the bell crank lever 118 in a clockwise direction. During the forward movement of the bar, a one-tooth rotation is imparted to the cam wheel 106 by the action of the tooth on the arm 126 of the pawl 124 on a tooth of the wheel. When the bar 112 is in normal retracted position, the pin 102 on the arm 100 is engaged between two of the teeth of the cam wheel 106, as clearly shown in Fig. 2. During this rotation of the cam wheel, the cam face of

one of the teeth engages the pin 102 and forces the same in a rearward direction. This swings the arm 100, the rock shaft 98 and the arm 96 in a counterclockwise direction, thereby actuating the tripping bail 78 to engage the carriage return clutch.

The bell crank lever 118 is swung in a clockwise direction to engage the carriage return clutch by the depression of any one of the keys 84, 86 and 88. The key bar 90 (see Figs. 2 and 5) is mounted for vertical sliding movement upon the side of the type carriage by means of pins or studs 132 and 133 fixed at their inner ends in the plate 110 and engaging in slots 134 and 136 in said bar. The key bar is normally held in elevated position by means of a coil spring 138. The key bar is provided with a lateral projection 140 arranged to engage a laterally bent flange 142 formed on the bell crank lever 118 to swing the bell crank in a clockwise direction as the key bar is depressed.

The key bar 92 (see Figs. 2 and 3) is mounted to slide vertically upon the side of the type carriage by means of the studs 132 and 133 which engage in slots 144 and 146 in the key bar. This key bar is acted upon by a coil spring 148 which normally maintains the key bar in an elevated position. This key bar is provided with a lateral projection 150 arranged to engage the laterally bent flange 142 on the bell crank lever 118 to swing the bell crank to engage the carriage return clutch upon the depression of the key bar.

The key bar 94 (see Figs. 2 and 4) is mounted to slide vertically on the side of the type head by means of the studs 132 and 133 which engage respectively in slots 152 and 154 in the key bar. This key bar is acted upon by coil spring 155 which normally maintains the bar in elevated position. The key bar is provided with a lateral projection 157 arranged to engage the laterally bent flange 142 on the bell crank lever 118 to swing said lever in a clockwise direction upon the depression of the key bar to engage the carriage return clutch.

Upon the depression of the key 84, the carriage is given a full return movement and is arrested in its limiting left-hand position. The carriage is arrested in different returned positions, each short of a complete return to the left-hand marginal position, following the depression of either of the keys 86 or 88.

When the bar 112 is moved to the right by the depression of one of the keys, it is latched in its right-hand position by a suitable latch mechanism. The latch is actuated to release the bar as the type carriage approaches the end of its return movement. The bar is then moved rearwardly to its normal position by the action of the spring 130. During this rearward movement of the bar, the inclined rear face of the arm 126 engages the cam face of the tooth 104 of the wheel 106 immediately to the rear of said arm and the arm rides over the tooth and finally drops down to the position shown in Fig. 2 with the tooth on the arm located to the rear of the tooth on the wheel, as shown in Fig. 2.

The mechanism for arresting the return movement of the carriage with the carriage in full return position or in either of two partial return positions comprises a vertically movable check stop 156 mounted on the carriage and arranged to engage any one of a series of arresters mounted on the draft rod 158. The check stop 156 is formed at the lower end of a slide 160 mounted for vertical sliding movement on the supporting

plate 110 and on the downwardly extending portion of an angle bracket 161 secured to the lower left-hand corner of the type head. To provide for this sliding movement, the upper end of the slide 160 is formed with a slot 162 in which engages a headed stud 164 fixed to the plate 110. The check stop is held in position with relation to the bracket 161 by means of a guide plate 166, the inner face of which is vertically grooved to accommodate slidably a laterally extended portion of the stop.

The mechanism co-operating with the check stop 156 to arrest the return movement of the carriage has substantially the same construction, arrangement and mode of operation as the corresponding mechanism illustrated and described in the patent to Sundstrand No. 2,283,401, dated May 19, 1942. Said mechanism comprises the draft rod 158 extending transversely of the line space frame. This rod is T-shaped in cross-section and is arranged to slide in a channel formed by the rear rail 20 of the line space frame, the web 168 projecting forwardly therefrom and the carriage escapement rack 170 being secured to the forward edge of said web. The left-hand end portion of the draft rod 158 is toothed for a considerable distance and arresters 172, 174 and 176 of different heights are adjustably arranged on the draft rod to be engaged by the check stop 156 to arrest the carriage during its return movement at any one of three precedent positions and also to effect a line-spacing operation incident to its return to any such precedent position. Arrester 172 of least height is located farthest to the right, and arresters 174 and 176 of successively greater heights are mounted on the draft rod in corresponding order to the left of the arrester 172. These arresters preferably have substantially the construction illustrated and described in said Patent No. 2,283,401 to enable them to be readily adjusted longitudinally on the draft rod.

The left-hand end of the draft rod 158 passes through an aperture in a rearwardly turned slotted projection 178 on the left-hand end of a slide 180 extending therefrom toward the right along the front face of the carriage escapement rack 170 to which the slide is connected by headed fastenings 182 engaging in slots 184 in the slide. The slide operates to guide the draft rod in its endwise travel and prevents it from canting in its channel.

The draft rod is provided at its right-hand end with a threaded portion 186 passing through a block 188 secured to the forward face of the arresting plate 190, the draft rod being fixed in said block by means of nuts 192 threaded on the rod and located upon opposite sides of the block. The arresting plate 190 is provided with parallel slots 194 and 196 in which engage respectively supporting and guiding members 198 and 200 extending from the line space frame to support and guide the plate.

The arresting plate 190 is formed with a beak 202 which projects toward the left from the upper left-hand edge of the plate into position to collide with a forwardly extending fixed stop 204 (Fig. 1) rigidly secured to the right-hand end of the rear rail 20.

A coiled spring 206 attached at one end to the fixed stop and connected at its opposite end to the draft rod 158 yieldingly retains the arresting plate 190, the draft rod and the slide 180 at their right-hand limits of travel as determined by contact of the left end wall of the slot 194

in the arresting plate with the guide member 198.

When the operator, at any point in the advance of the carriage, desires to return the carriage to its limiting left-hand position or to give a full return movement to the carriage, he depresses the key 84 and the key bar 92 to their limiting positions determined by the engagement of the pin 183 with the upper end of the slot 136. During the downward movement of the key bar, the bell crank 118, bar 112, pawl 124, toothed wheel 106, pin 102, arm 108, shaft 98 and arm 96 are actuated to swing forwardly the carriage return ball 78 and thereby engage the carriage return clutch to initiate the return movement of the carriage. After being actuated by the key lever, the parts of the clutch engaging mechanism between the arm 96 and the clutch are maintained in position until the carriage approaches the end of its return movement. The check stop 156 is not depressed by this operation but remains in its uppermost position.

During the return movement of the carriage, the check stop 156 passes over the graduated arresters 172 and 174 and finally engages the highest arrester 176, the location of which on the draft rod determines the beginning of a line of writing.

The check stop 156, when in its elevated position, will clear the arresters 172 and 174 during the return movement of the carriage and will engage the arrester 176 to stop the carriage in full return position. The check stop is depressed to one predetermined position such that it will clear the arrester 172 and will engage the arrester 174 during the return movement of the carriage by the depression of the key 86. The check stop is depressed to another predetermined position such that it will engage the arrester 172 during the return movement of the carriage by the depression of the key 88.

The mechanism for depressing the check stop comprises a bell crank lever 208 pivoted on a stud 210 fixed at its inner end in the supporting plate 110. The lever 208 is formed with a slot 212 in the rearwardly extending arm thereof in which engages a headed pin 214 secured in the slide 160. The upwardly extending arm of the bell crank lever 208 is connected by a link 216 with a lever 218 pivoted at 220 on the supporting plate 110. The link 216 is acted upon by a coil spring 234 which tends constantly to move the link and the lever 218 forwardly. This lever carries a roller 222 arranged to be engaged by the rear edge of a plate 224 adjustably pivoted at 226 on the key bar 92 and held in adjusted position by means of a screw 228 engaging in a slot 230 in the plate and threaded into the key bar. The plate 224 is formed with a cam face 232 arranged to engage the roller 222 during the first part of the downward movement of the key bar and with a face 234 substantially parallel with the direction of movement of the key bar which engages the roller 222 during the latter part of the downward movement of the bar.

As the key bar 92 is moved downwardly by the depression of the key 86, the lever 218 is swung about its pivot 220, in a clockwise direction, by the engagement of the cam face 232 with the roller 222 to actuate the bell crank lever 208 to depress the slide 160 and the check stop to a position in which the check stop will pass over the arrester 172 and will engage the arrester 174 during the return movement of the carriage.

When the check stop has been projected into

position to engage the arrester 174, the stop is held in projected position while the key 86 and key bar 92 are depressed by the engagement of the roll 222 with the edge face 234 of the plate 224.

The rear edge of the key bar 94 is also arranged to engage the roller 222 on the lever 218. In order to depress the check stop by the downward movement of the key bar 94, the bar is formed with a cam face 236 (see Fig. 4) arranged to engage the roller 222 during the early part of the downward movement of the key bar from elevated position. The key bar 94 is also formed with a face 238 substantially parallel with the direction of movement of the bar which is engaged with the roller 222 during the latter part of the downward movement of the key bar.

By the depression of the key 88 and key bar 94, the lever 218 is actuated through the cam face 236 to project the slide 160 and check stop 156 downwardly to a position in which the stop engages the arrester 172 during the return movement of the carriage.

When the check stop has been projected into position to engage the arrester 172, the stop is held in projected position while the key 88 and key bar 94 are depressed by the engagement of the roll 222 with the edge face 238 of the key bar.

It is highly desirable that mechanism should be provided for holding the check stop 156 in either of the positions into which it is projected respectively by the depression of the keys 86 and 88 after a depression and release of either of said keys. Otherwise, it would be necessary for the operator to maintain each of these keys in depressed position during the return of the carriage to stop the carriage in the desired partial return position. In the present machine, this result is secured by providing mechanism for holding each of the key bars 92 and 94 in depressed position following its depression substantially until the completion of the return of the carriage. The mechanism for holding down these key bars also operates, after the depression of key 84, to hold down the key bar 92 during the return of the carriage although this key bar does not control the check stop. The mechanism for holding down the several key bars and corresponding keys, during the return of the carriage, is operated to release the keys bars at the end of the carriage return movement.

The mechanism for holding down the key bars when depressed respectively comprises a projection or locking lug 240 formed on the forward end of the longitudinally movable bar 112.

The key bars 90, 92 and 94 are formed respectively with laterally projecting locking lugs 242, 244 and 246 for co-operating with the lug 240. When a key bar is depressed thereby actuating the bell crank 118 to move the bar 112 longitudinally forward or to the right, Figs. 2 and 3, the corresponding locking lug 242, 244 or 246 extending laterally from the bar is depressed below the projection 240 and said projection is moved forwardly above said locking lug as shown in Fig. 3 by the forward movement of bar 112. The key bar thus will be held down by the engagement of the locking lug on the bar 112 with the projection 240 as long as the bar 112 remains in forward position. The locking of the key bars 92 and 94 in depressed position will also lock the check stop, which is controlled by said key bars, in depressed position.

locates the projection 240 above the laterally extending locking lug on the depressed key bar, also locates said projection below the corresponding locking lug on the other two key bars. These key bars therefore are then locked against depression while the bar 112 remains in its forward position.

The bar 112 is held in its forward position, following the depression of a key bar, during the return of the carriage until the tripping ball 78 is swung back rearwardly to disengage the carriage return clutch. The bar 112 is released at this time and allowed to move back to its rear position under the influence of spring 130.

15 The disconnection of the motor from the carriage is automatically effected, regardless of the extent of return travel of the carriage, by a mechanism adapted to function just prior to the arrest of the carriage at any of its completely or partially returned stations. The said mechanism comprises a floating thrust bar 248 slidably supported adjacent its left-hand end in an eye 250 formed in a bracket secured to and projecting from the adjacent vertical bracket 10 on the line space frame. The thrust bar is slotted at its right-hand end as at 252 to ride on the rear end of a stud 254 projecting rearwardly from and travelling with the arresting plate 190. The left-hand end of the thrust bar is arranged to engage an inclined cam face on a member 256 secured to the right-hand end of the trip bail 18 in the path of travel of the thrust bar.

The length of the slot 252 in the thrust bar is less than the distance normally between the beak 202 and the fixed stop 204. Therefore, as the arresting plate 190 is drawn to the left by contact of the check stop 156 with one of the arresters 172, 174 or 176, the supporting stud 254 will travel idly along the slot 252 of the thrust bar until shortly prior to the arrest of the plate 190 by contact of the beak 202 with the stop 204, the supporting stud 254 reaches the left end wall of the slot 252. Thereafter, the continued movement of the arresting plate 190 shifts the thrust rod to the left against the inclined face of the contact member 256 on the trip bail and rocks the trip bail back to its normal position, thereby disconnecting the shiftable driven clutch member of the carriage return clutch from the driving clutch member.

50 The bar 112 is held in forward position by a pivoted latch. This rearward movement of the trip bail operates the latch to release the bar. The latch indicated at 258 is located between the
55 rear end of the bar and the slide 160 and is pivoted on the stud 168 upon which the toothed wheel 166 is journaled. The latch is actuated upon

60 wheel 166 is journaled. The latch is acted upon by a coil spring 260 which tends constantly to swing the latch upwardly into latching position. When the bar 112 is located in its normal or rear position, the upper edge of the latch is held in engagement with a laterally bent projection 262 formed on the bar, as shown in Fig. 2. When the bar 112 is moved forwardly upon the depression

65 bar 112 is moved forwardly upon the depression of one of the key bars, the latch is swung upwardly behind the projection 262 to latch the bar in forward position, the upward movement of the latch then being limited by the engagement of an arm 266 extending rearwardly from the 70 body of the latch with the pin 102. The latch holds the bar 112 in forward position until the tripping bail 78 is swung rearwardly to disengage the carriage return clutch, as above stated. The rearward movement of the bail then swings the

The forward movement of the bar 112, which 75 arm 96, the shaft 98 and the arm 100 in a clock-

11

wise direction. During this clockwise swinging movement of the arm 100, the pin 102 on said arm engages a cam-shaped edge portion 264 formed on the arm 266 and swings the latch in a clockwise direction about the stud 108, thereby disengaging the forward end of the latch from behind the projection 262 on the bar 112. The bar is then moved back to its rearward position by the action of the spring 130.

Thus following the depression of one of the key bars, the bar 112 is held in forward position and the key bar and the check stop 156 are held in depressed positions during the return of the carriage until the check stop has engaged one of the arresters 172, 174, 176 and the draft rod 158 has been moved some distance to the left, Fig. 1. The leftward movement of the draft rod moves the stop plate 190 to the left and, during the latter part of the movement of said plate, the plate picks up the thrust bar 248 and said bar is actuated to engage the inclined face on the contact member 256 to swing back the carriage return or tripping bail 78.

The parts of the present mechanism are constructed and arranged so that, when the latch 258 is in its upper or latching position and the carriage return bail is in forward position, the latch is actuated to disengage the projection 262 on the bar 112 and thereby release said bar for rearward movement to unlock the depressed key during the latter part of the rearward movement of the bail by which the carriage return clutch is disengaged. As shown in Fig. 3, the bail 78 is located in spaced relation to the arm 96 when the carriage return clutch is engaged and the latch is in its upper position. After the latch is thrown out, the upward movement of the slide 160 is delayed until after the first part of the upward movement of the depressed key bar by the engagement of the edge of the key bar substantially parallel with the direction of movement of said bar with the roller 222. These features of the present mechanism are provided to prevent the projectible stop from being elevated out of engagement with the arrester until the return movement of the carriage is completely arrested.

Normally, after the arrest of the return movement of the carriage, the slide 160 will be moved upwardly by the action of the spring 231 on the link 216 and the bell crank 208 to elevate the projectible stop 156. In the event that the friction between the check stop and the arrester prevents the elevation of the slide 160 upon the arrest of the return movement of the carriage, the friction between these parts will be relieved sufficiently to allow the slide 160 to be actuated to elevate the check stop upon the movement of the carriage for a relatively slight distance in letter-spacing direction.

It is to be understood that the construction shown and described in this application is merely illustrative of the invention and that the several features thereof, except as defined in the claims, are not limited to the particular construction and arrangement of parts of the illustrated embodiment of the invention but that the invention may be embodied in other forms within the scope of the claims.

Having explained the nature and object of the invention and having specifically described a machine embodying the various features of the invention, in their preferred forms, what is claimed is:

1. In a record making machine, a transversely movable carriage, mechanism for moving the car-

12

riage in one direction during a record making operation, power mechanism for imparting return movements to the carriage, two or more independently operable manipulative devices for rendering operative said power mechanism, means common to all said devices and movable thereby for retaining an operated one of said devices in actuated position during the return of the carriage and means operated by said carriage for releasing automatically said devices.

2. In a record making machine, a transversely movable carriage, mechanism for moving the carriage in one direction during a record making operation, power mechanism for imparting return movements to the carriage, two or more independently operable manipulative devices for rendering operative said power mechanism, means common to all said devices and movable thereby into a position for retaining an operated one of said devices in actuated position during the return of the carriage, latching means for said retaining means, and means operated by said carriage adjacent the end of the carriage return movement for releasing said latching means.

3. A record making machine comprising a carriage, means for moving the carriage transversely of the machine during the making of a record, power mechanism for imparting return movements to the carriage, stopping means for arresting the return movement of the carriage in different returned positions, two or more independently operable manipulative devices for controlling said stopping means to arrest the carriage selectively in any one of the different returned positions, means common to said devices for retaining an operated one of said devices in actuated position during the return of the carriage and means for releasing automatically said devices.

4. A record making machine comprising a carriage, means for moving the carriage transversely of the machine during the making of a record, power mechanism for imparting return movements to the carriage, stopping means for arresting the return movement of the carriage in different returned positions, two or more independently operable manipulative devices for controlling said stopping means to arrest the carriage selectively in any one of the different returned positions, means common to said devices and moved thereby for retaining an operated one of said devices in actuated position during the return of the carriage, latching means for said retaining means and mechanism for throwing out of action said latching means to release said retaining means and said devices adjacent the end of the carriage return movement.

5. In a record making machine, a carriage movable in opposite directions across the machine, means for moving the carriage across the machine in one direction during a record making operation, power mechanism for imparting return movements to the carriage, stopping means for arresting the return movement of the carriage, a first manipulative device, a second manipulative device, means common to both said devices and operable thereby for causing the power mechanism to return the carriage and for controlling the stopping means to stop the carriage substantially in one or the other of two predetermined positions, mechanism for retaining each of said devices and said common means, after being actuated, in actuated position during the return of the carriage and means for releasing automatically said devices and said common means.

6. In a record making machine, a carriage movable in advance and return directions transversely of the machine, means for moving the carriage transversely of the machine in one direction during a record making operation, power mechanism for imparting return movements to the carriage, stopping means for arresting the return movement of the carriage, a manipulative device means operable thereby for causing the power mechanism to return the carriage and for controlling the stopping means to stop the carriage substantially in a predetermined position, a second manipulative device engageable with said operable means for causing the power mechanism to return the carriage and for controlling the stopping means to stop the carriage substantially in another predetermined position, mechanism for retaining each of said devices and said operable means, following their actuation, in actuated position during the return of the carriage, and means for releasing automatically said retained devices and means adjacent the end of the carriage return movement.

7. A record making machine comprising a carriage movable transversely across the machine, means for moving the carriage in one direction during a record making operation, power operated mechanism for returning the carriage comprising engageable and disengageable driving connections, a bail extending in a direction transversely of the machine and fixed in said direction, mechanism operated by the bail for engaging and disengaging said connections, means comprising a rotatable toothed cam wheel for shifting said bail, manipulative means and mechanism operated by said manipulative means for rotating the cam wheel.

8. In a record making machine, a transversely movable carriage, mechanism for moving said carriage across the machine in one direction during a record making operation, power actuated mechanism, normally disconnected from the carriage, for moving the carriage in the opposite direction to return the same, manipulative means, a rotatable multi-toothed cam wheel, mechanism driven by said manipulative means upon each manipulation thereof for rotating said cam wheel one tooth space, and means operated by said toothed cam wheel for connecting said power actuated mechanism with said carriage.

9. A record making machine comprising a carriage mounted for movement across the machine, mechanism for advancing the carriage during a record making operation, mechanism driven by power and normally disconnected from the carriage for returning the carriage, a plurality of manipulative devices, a rotatable multi-toothed cam wheel, mechanism driven by each of said devices upon manipulation thereof for rotating the cam wheel one tooth space, and means operated by said toothed cam wheel for connecting said power driven mechanism with said carriage.

10. In a record making machine, a carriage movable in opposite directions across the machine, means for moving the carriage in one direction during a record making operation, power driven mechanism for imparting return movements to the carriage, means for connecting the carriage with said power driven mechanism including a rotatable toothed cam wheel, a pawl for rotating said wheel, a manipulative device and means operated by each actuation of said device to move the pawl to impart a partial rotation to said cam wheel.

11. A record making machine comprising a

carriage movable transversely across the machine, means for moving the carriage in one direction during a record making operation, power mechanism for returning the carriage in the opposite direction, mechanism for connecting the carriage with the power mechanism including a rotatable toothed cam wheel, a pawl for actuating the wheel, a support movable in opposite directions upon which said pawl is movably mounted, manually controlled means and mechanism operated by the latter means for shifting said support to cause the pawl to impart a partial rotation to the wheel.

12. A record making machine comprising a carriage mounted for movement across the machine, means for moving the carriage in one direction during a record making operation, power mechanism for returning the carriage comprising engageable and disengageable driving connections, a bail, mechanism operated by the bail for engaging and disengaging said connections, means comprising a rotatable toothed cam wheel for shifting said bail, a slide, a pawl movably mounted on the slide for engaging said wheel, a manipulative device, means operated by said device for moving the slide in one direction to cause the pawl to impart a partial rotation to said wheel, a latch for holding the slide in operated position and means operated by the bail for disengaging the latch.

13. In a record making machine, a carriage, means for moving the carriage in one direction across the machine in the making of a record, power mechanism for imparting return movements to the carriage, mechanism for arresting the return movements of the carriage, means for controlling said carriage return and arresting mechanisms comprising a series of manipulative devices, a locking device for locking each of said manipulative devices, following its actuation, in actuated position during the return of the carriage, a latch for retaining said locking device in locking position and means for automatically releasing the latch.

14. In a record making machine, a carriage, means for moving the carriage in one direction across the machine in the making of a record, power mechanism for imparting return movements to the carriage, mechanism for arresting the return movements of the carriage, means for controlling said carriage return and arresting mechanisms comprising a series of manipulative devices, a locking device for locking each of said manipulative devices, following its operation, in operated position during the return of the carriage, a latch for retaining said locking device in locking position and means for automatically releasing the latch adjacent the end of the return movement of the carriage.

15. In a record making machine, a carriage movable in advance and return directions transversely of the machine, mechanism for moving the carriage across the machine in one direction during a record making operation, power mechanism for imparting return movements to the carriage, stopping means for arresting the return movement of the carriage comprising a projectible stop, a manipulative device and connections for projecting the stop, means for locking the device and thereby the stop in actuated position, mechanism operated by the actuation of said device for moving the locking means into locking position, a latch for holding the locking means in locking position during the return of the car-

15

riage and means for automatically throwing out the latch.

16. In a record making machine, a transversely movable carriage, mechanism for moving the carriage across the machine in one direction, power operated mechanism for imparting return movements to the carriage, mechanism for arresting the return movements of the carriage comprising a projectible stop, manipulative devices and connections respectively for projecting the stop to different stopping positions, means for locking each of said devices and thereby the stop in actuated position during the return of the carriage, mechanism operated by each of said devices for moving the locking means into locking position, a latch for holding the locking means in locking position during the return of the carriage and means for automatically rendering inactive the latch.

17. In a record making machine, a carriage 20 movable in opposite directions across the machine, means for moving the carriage across the machine in one direction during a record making operation, power mechanism for imparting return movements to the carriage, stopping means 25 for arresting the return movement of the car-

5
10

16

riage at a predetermined position, a manipulative device, connections operated by said manipulative device for causing the power mechanism to return the carriage, a second manipulative device for operating said connections for causing the power mechanism to return the carriage and for controlling the stopping means to stop the carriage substantially in a different predetermined position, mechanism for retaining each of said devices and said connections, after being actuated, in actuated position during the return of the carriage, and means operated by said stopping mechanism for releasing automatically said retaining mechanism.

OSCAR W. SWANSON.
